(57) **ABSTRACT**

In connectors including a housing having a separation wall, an impedance of a portion of a terminal in close proximity to the separation wall is suppressed from dropping excessively.

Housings of the connector include a separation wall positioned between adjacent terminals. The separation wall includes a one-side opposing face and an other-side opposing face. Furthermore, the separation wall is formed between the one-side opposing face and the other-side opposing face, and includes a gap portion positioned between the adjacent terminals.

FACES FOR SUPPRESSING EXCESSIVE
IMPEDANCE DROP**

**CROSS-REFERENCE TO RELATED
APPLICATION**

This application claims priority under 35 USC 119 from Japanese Patent application No. 2022-044558 filed on Mar. 18, 2022, the disclosure of which is incorporated by reference herein in its entirety.

TECHNICAL FIELD

The present disclosure relates to a connector.

BACKGROUND ART

A connector of Japanese Patent Application Laid-Open (JP-A) No. 2015-76215 includes plural terminals and a housing. Each of the plural terminals includes a contact portion for contacting a connection target. The housing includes a separation wall disposed between adjacent of the contact portions.

SUMMARY OF INVENTION

Technical Problem

In a connector such as described above, a separation wall is formed from an insulator that is the material of the housing. This means that the impedance of the contact portion disposed in close proximity to the separation wall sometimes drops excessively.

An issue addressed by the present disclosure is, in a connector including a housing with separation wall, to suppress the impedance of a portion of the terminal in close proximity to the separation wall from dropping excessively.

Solution to Problem

A connector according to a first aspect is a connector including plural terminals and a housing. The housing includes a separation wall positioned between adjacent of the terminals. The separation wall includes a one-side opposing face that opposes one of the adjacent terminals, an other-side opposing face that opposes the other of the adjacent terminals, and a gap portion formed between the one-side opposing face and the other-side opposing face.

The present aspect is a connector including the plural terminals and the housing.

The housing includes the separation wall positioned between the adjacent terminals. The separation wall includes the one-side opposing face and the other-side opposing face. The one-side opposing face is a face that opposes the one adjacent terminal, and the other-side opposing face is a face that opposes the other adjacent terminal.

Furthermore, the separation wall includes the gap portion formed between the one-side opposing face and the other-side opposing face.

This thereby raises the impedance of a close proximity portion of each of the terminals corresponding to the gap portion in comparison to embodiments not formed with such a gap portion. As a result thereof, the impedance of the terminals can be suppressed from falling excessively.

Note that in the exemplary embodiment described later an example is described in which “plural terminals” are all the terminals provided to the connector. However, the “plural terminals” of the present aspect is not limited thereto. The 5 “plural terminals” of the present aspect may be two terminals from out of many terminals provided to the connector, or may be three terminals therefrom. In other words, the connector of the present aspect may also be provided with terminals other than the “plural terminals” of the present aspect.

Moreover, in the exemplary embodiment described later an example is described in which the “plural terminals” have the same structure as each other. However, the plural terminals” of the present aspect are not limited thereto.

15 Moreover, in the exemplary embodiment described later an example is described in which the gap portion is open in a direction perpendicular to a terminal array direction. However, the gap portion of the present embodiment is not limited thereto, and may, for example, not be open in any 20 direction.

Moreover, in the exemplary embodiment described later an example is described in which the “housing” includes a fixed housing and a movable housing. However, the “housing” of the present aspect is not limited thereto and may be 25 configured by a fixed housing alone. Namely, the connector is not necessarily a so-called floating connector.

Moreover, in the exemplary embodiment described later an example is described in which air is disposed in the gap portion. However, the gap portion of the present aspect is not 30 limited thereto and, for example, a member having a lower permittivity than the housing may be disposed therein.

Moreover, although in the exemplary embodiment described later an example is described in which the gap portion is positioned between adjacent terminals (an 35 example of the gap portion being positioned at a position sandwiched by adjacent terminals), the present aspect is not limited thereto. The reason for this is that even in an embodiment in which a gap portion cannot be said to be positioned between the adjacent terminals (including an 40 embodiment in which the adjacent terminals have different shapes from each other), a gap portion still exhibits advantageous effects for adjusting impedance.

A connector according to a second aspect is the first aspect, wherein the terminals each include a restricted portion, the one-side opposing face includes a one-side 45 restricting face that restricts one of adjacent of the restricted portions from moving in a direction approaching the other thereof, the other-side opposing face includes an other-side restricting face that restricts the other adjacent restricted portion from moving in a direction approaching the one 50 thereof, and the restricted portion includes a contact portion configured to contact a connection target.

In the present aspect the terminals include the restricted portions. The one-side opposing face includes the one-side 55 restricting face that restricts the one adjacent restricted portion from moving in the direction approaching the other thereof, and the other-side opposing face includes the other-side restricting face that restricts the other adjacent restricted portion from moving in the direction approaching the one thereof.

Part of the terminal (the restricted portion thereof) is 60 accordingly suppressed from being disposed at a position displaced from a specific position. Note that reference to a restricted portion means a portion restricted from moving in the respective directions mentioned above by the one-side restricting face or the other-side restricting face of the separation wall.

Moreover, the restricted portion includes a contact portion for contacting the connection target.

This means that the contact portion is suppressed from being disposed at a position displaced from a specific position.

Note that although in the exemplary embodiment described later an example is described in which the gap portion is positioned between adjacent of the restricted portions (contact portions), the present aspect is not limited thereto. However, the restricted portion is disposed in close proximity to the separation wall and so the impedance is liable to drop excessively. Thus preferably the gap portion is positioned between the adjacent restricted portions (contact portions).

Moreover, although in the exemplary embodiment described later an example is described in which the terminals each include plural restricted portions (a first contact portion and a second contact portion), the present aspect is not limited thereto.

A connector according to a third aspect is the second aspect, wherein the contact portion includes a first contact portion and a second contact portion positioned further to a far side than the first contact portion in a connection direction of the connection target, and the gap portion is positioned between adjacent of the first contact portions and is positioned between adjacent of the second contact portions.

In the present aspect the contact portion includes the first contact portion and the second contact portion positioned further to the far side than the first contact portion in the connection direction of the connection target.

The gap portion is positioned between the adjacent first contact portions and is positioned between the adjacent second contact portions.

This accordingly enables the first contact portion and the second contact portion to be suppressed from being disposed at positions displaced from specific positions, and enables the impedances of the first contact portion and the second contact portion to be suppressed from dropping excessively.

A connector according to a fourth aspect is the third aspect, wherein a portion of the gap portion positioned between the adjacent first contact portions and a portion of the gap portion positioned between the adjacent second contact portions are coupled together in the connection direction.

In the present aspect the portion of the gap portion positioned between the adjacent first contact portions and the portion of the gap portion positioned between the adjacent second contact portions are coupled together in the connection direction.

This means that the gap portion is more easily formed than embodiments in which a portion of the gap portion positioned between the adjacent first contact portions and a portion thereof positioned between the adjacent second contact portions are not coupled together.

A connector according to a fifth aspect is any one of the second aspect to the fourth aspect, wherein each of the plural terminals includes a resilient support portion that resiliently supports the contact portion, and the separation wall is configured so as to be interposed between adjacent of the resilient support portions.

In the present aspect each of the plural terminals includes a resilient support portion that resiliently supports the contact portion.

The separation wall is configured so as to be interposed between adjacent of the resilient support portions.

Shorting between the adjacent resilient support portions caused by metal-plating gas is thereby prevented at the

portion where the separation walls are interposed between the adjacent resilient support portions.

In the exemplary embodiment described later (except for the first modified example), an example is described in which the separation wall is configured so as to be interposed between the entirety of the adjacent resilient support portions, however the separation wall of the present aspect is not limited thereto. For example as in the first modified example, the separation wall of the present aspect may be configured so as to be interposed between part of adjacent resilient support portions.

The connector according to a sixth aspect is the fifth aspect, wherein the separation wall includes either a one-side separated face that is a face facing a side of one of the adjacent resilient support portions and that is formed at a position separated from the one adjacent resilient support portion further than the one-side restricting face in an adjacency direction of the adjacent resilient support portions, or an other-side separated face that is a face facing toward a side of the other adjacent resilient support portion and that is formed at a position separated from the other adjacent resilient support portion further than the other-side restricting face in the adjacency direction of the adjacent resilient support portions, or both thereof.

In the present aspect the separation wall includes either the one-side separated face, or the other-side separated face, or both thereof.

The one-side separated face is a face that faces toward the side of the one adjacent resilient support portion and that is formed at the position separated from the one adjacent resilient support portion further than the one-side restricting face in the adjacency direction (the direction in which the adjacent resilient support portion are adjacent to each other). The other-side separated face is a face that faces toward the side of the other adjacent resilient support portion, and that is formed at the position separated from the other adjacent resilient support portion further than the other-side restricting face in the adjacency direction.

This thereby enables the impedance of the resilient support portion to be suppressed from dropping excessively in comparison to embodiments in which the separation wall lacks the one-side separated face and the other-side separated face.

A connector according to a seventh aspect is the sixth aspect, wherein the one-side separated face or the other-side separated face provided to the separation wall includes a near-side separated face formed at a position displaced from a position of the one-side restricting face or the other-side restricting face in an opposite direction to a contact direction in which the contact portion contacts the connection target.

In the present aspect the one-side separated face or the other-side separated face provided to the separation wall includes the near-side separated face. The near-side separated face is the face formed at the position displaced from the position of the one-side restricting face or the other-side restricting face in the opposite direction (hereafter referred to as "opposite-to-contact direction") to the contact direction (the direction in which the contact portion contacts the connection target).

This means that when part of the resilient support portion is disposed at the position displaced from the position of the contact portion in the opposite-to-contact direction, then the impedance of this part of the resilient support portion can be suppressed from dropping excessively.

A connector according to an eighth aspect is the sixth aspect of the seventh aspect, wherein the one-side separated face or the other-side separated face provided to the sepa-

ration wall includes a first far-side separated face formed at a position displaced from a position of the one-side restricting face or the other-side restricting face toward a far side in a connection direction of the connection target.

In the present aspect the one-side separated face or the other-side separated face provided to the separation wall includes the first far-side separated face. The first far-side separated face is a face formed at the position displaced from the position of the one-side restricting face or the other-side restricting face toward a far side in the connection direction of the connection target.

This means that when part of the resilient support portion is disposed at the position displaced from the position of the contact portion toward the far side in the connection direction, then the impedance of this part of the resilient support portion can be suppressed from dropping excessively.

A connector according to a ninth aspect is any one of the sixth aspect to the eighth aspect, wherein the one-side separated face or the other-side separated face provided to the separation wall includes a second far-side separated face formed at a position that is displaced from a position of the one-side restricting face or the other-side restricting face in an opposite direction to a contact direction in which the contact portion contacts the connection target and toward a far side in the connection direction of the connection target.

In the present aspect the one-side separated face or the other-side separated face includes the second far-side separated face. The second far-side separated face is a face formed at the position displaced from the position of the one-side restricting face or the other-side restricting face in the opposite-to-contact direction and toward the far side in the connection direction.

This means that in cases in which part of the resilient support portion is disposed at the position displaced from the position of the contact portion in the opposite-to-contact direction and toward the far side in the connection direction, the impedance of this part of the resilient support portion can be suppressed from dropping excessively.

A connector according to a tenth aspect is the first aspect, wherein the restricted portion includes a contact portion configured to contact a connection target, and the contact portion includes a first contact portion, and a second contact portion positioned further to a far side than the first contact portion in a connection direction of the connection target. Each of the plural terminals includes a resilient support portion that resiliently supports the contact portion. The separation wall is configured so as to be interposed between adjacent of the resilient support portions. The separation wall includes either a one-side separated face that is a face facing a side of one of the adjacent resilient support portions and that is formed at a position separated from the one adjacent resilient support portion further than the one-side restricting face in an adjacency direction of the adjacent resilient support portions, or an other-side separated face that is a face facing toward a side of the other adjacent resilient support portion and that is formed at a position separated from the other adjacent resilient support portion further than the other-side restricting face in the adjacency direction of the adjacent resilient support portions, or both thereof. The one-side separated face or the other-side separated face provided to the separation wall includes a near-side separated face formed at a position displaced from a position of the one-side restricting face or the other-side restricting face in an opposite direction to a contact direction in which the contact portion contacts the connection target, a first far-side separated face formed at a position displaced from a position of the one-side restricting face or the

other-side restricting face toward a far side in a connection direction of the connection target, and a second far-side separated face formed at a position that is displaced from a position of the one-side restricting face or the other-side restricting face in an opposite direction to the contact direction in which the contact portion contacts the connection target and toward a far side in the connection direction of the connection target.

In the present aspect, in cases in which the terminals 10 include the contact portion and the resilient support portion with the contact portion including the first contact portion and the second contact portion, shorting between the adjacent resilient support portions caused by metal-plating gas can be prevented and the impedance of the resilient support portion can be suppressed from dropping excessively.

A connector according to an eleventh aspect is the first aspect, wherein the terminals each include a first contact element and a second contact element. The first contact element includes a first contact portion and a first resilient support portion that resiliently supports the first contact portion. The second contact element includes a second contact portion positioned further to a far side than the first contact portion in a connection direction of a connection target and a second resilient support portion that resiliently supports the second contact portion.

In the present aspect the terminals include the first contact element and the second contact element. The first contact element includes the first contact portion and the first resilient support portion that resiliently supports the first contact portion. The second contact element includes the second contact portion positioned further to the far side than the first contact portion in the connection direction of the connection target and the second resilient support portion that resiliently supports the second contact portion. This 35 thereby enables the connection reliability to be raised.

Moreover, in cases in which the terminals include the first contact element and the second contact element, although the impedance of the first contact element and the second contact element is liable to drop excessively, in the present 40 aspect the gap portion is provided, enabling the impedance of the first contact element and the second contact element to be suppressed from dropping excessively.

Note that although in the exemplary embodiment described later an example is described in which the gap portion is positioned between the adjacent first contact portions and positioned between the adjacent second contact portions, the present aspect is not limited thereto. The present aspect encompasses configurations in which, although the gap portion is not positioned between the adjacent first contact portions and second contact portions, the gap portion is positioned between the adjacent first contact elements and positioned between the adjacent second contact elements. Furthermore, the present aspect also encompasses configurations in which the gap portion is not positioned between the adjacent first contact elements and second contact elements. This is because even when the gap portion is not positioned at such positions, the gap portion still exhibits advantageous effects for adjusting impedance of the first contact element and the second contact element.

BRIEF DESCRIPTION OF DRAWINGS

FIG. 1 is a cross-section of a connector.

FIG. 2 is a perspective view of a connector.

FIG. 3 is an exploded perspective view of a connector.

FIG. 9 is a cross-section perspective view illustrating a second modified example.

FIG. 10 is a cross-section perspective view illustrating a third modified example.

FIG. 11 is a cross-section perspective view illustrating a fourth modified example.

DESCRIPTION OF EMBODIMENTS

Description follows regarding a connector 100 that is an exemplary embodiment of a connector of the present disclosure.

In each of the drawings, an arrow X will be referred to as a connector front-rear direction, an arrow Y as a connector width direction, and an arrow Z as a connector up-down direction.

Connector 100

As illustrated in FIG. 1 to FIG. 3, the connector 100 includes housings 10, 20, and plural terminals 30. The housings 10, 20 include a fixed housing 10 and a movable housing 20.

The fixed housing 10 is a housing fixed to a board B1 that is a mounting target of the connector 100. The fixed housing 10 is fixed to the board B1 through the plural terminals 30.

The movable housing 20 is a housing provided so as to be able to move with respect to the fixed housing 10. The movable housing 20 is supported by the plural terminals 30 in a floating state.

The fixed housing 10 and the movable housing 20 are formed from an insulator such as a synthetic resin or the like.

The terminals 30 are connected to the board B1 and to counterpart terminals (omitted in the drawings) of a counterpart connector (omitted in the drawings). The terminals 30 are made by performing punch and bending processing and the like to a conductive plate material. Each of the plural terminals 30 has the same shape as each other.

The plural terminals 30 are configured from plural (four in the drawing) front-side terminals 30 and by plural (four in the drawing) rear-side terminals 30. A front-side terminal 30 and a rear-side terminal 30 together configure a pair of terminals 30 (see FIG. 4), and these pairs of terminals 30 can be thought of as being arrayed with the Y direction as their array direction. The terminals 30 in a pair are arranged opposing each other such that their contact portion-side directions (direction of the positions of contact portions 35b1, 35b2 with respect to a connection portion 31 when viewed along the Z direction) face toward the X direction inside.

Next, detailed description follows regarding the terminals 30.

As illustrated in FIG. 4, the terminals 30 each include the connection portion 31, a fixed-side retained portion 32, an intermediate portion 33, a movable-side retained portion 34, and a leading end portion 35, in that order.

The connection portion 31 is a portion connected to the board B1 that is the mounting target.

The connection portion 31 extends from the fixed-side retained portion 32 toward the X direction outside, this being

a direction along a plane of the board B1. The connection portion 31 is soldered to a face of the board B1.

The fixed-side retained portion 32 is a portion retained in the fixed housing 10.

5 The fixed-side retained portion 32 is retained in the fixed housing 10 by being press-fitted into the fixed housing 10 with a +Z direction as the press-fit direction. The fixed-side retained portion 32 has a plate width direction (the plate width direction of the fixed-side retained portion 32 is sometimes referred to as a "first plate width direction") facing in the Y direction that is the terminal array direction, and extends in the +Z direction. The fixed-side retained portion 32 includes press-fit protrusions 32a. The press-fit protrusions 32a are formed at both plate width direction sides of the fixed-side retained portion 32.

10 The intermediate portion 33 is a portion that couples the fixed-side retained portion 32 and the movable-side retained portion 34 together, and is a portion formed deformable so as to enable the movable-side retained portion 34 to displace with respect to the fixed-side retained portion 32.

15 The intermediate portion 33 includes a first coupling portion 33a, a plate thickness direction switching portion 33b, and a second coupling portion 33c, in this order.

20 The first coupling portion 33a couples the fixed-side retained portion 32 and the plate thickness direction switching portion 33b together. The first coupling portion 33a extends from the fixed-side retained portion 32 to a first plate face portion 33b1 of the plate thickness direction switching portion 33b, and has a plate thickness direction facing in a direction parallel to a ZX plane (a plane perpendicular to the first plate width direction).

25 The first coupling portion 33a includes a first bent portion 33a1.

30 The first bent portion 33a1 couples the fixed-side retained portion 32 and the first plate face portion 33b1 of the plate thickness direction switching portion 33b together. The first bent portion 33a1 is a portion bent in the plate thickness direction, and switches a Z direction component of the extension direction of the terminals 30 from plus to minus.

35 The plate thickness direction switching portion 33b switches the plate thickness direction of the terminal 30 from the ZX plane direction to the Y direction (a direction orthogonal to the ZX plane).

40 The plate thickness direction switching portion 33b includes a switching-bend portion 33b2, the first plate face portion 33b1, and a second plate face portion 33b3.

45 The switching-bend portion 33b2 is a portion bent in the plate thickness direction, and couples the first plate face portion 33b1 and the second plate face portion 33b3 together.

50 The first plate face portion 33b1 is formed at a fixed-side retained portion 32 side with respect to the switching-bend portion 33b2. The first plate face portion 33b1 has a flat plate shape, with a plate thickness direction facing in the ZX plane direction.

55 The first plate face portion 33b1 can be thought of as being a portion connected to the first coupling portion 33a and extending toward the other end side (contact portion 35b1, 35b2 side) of the terminal 30. When thought of in this manner, the first plate face portion 33b1 is a portion having an extension direction having a straight line shape. The extension direction of the first plate face portion 33b1 is a direction inclined toward the -Z direction and the X direction inside. The plate width direction of the first plate face portion 33b1 faces along the Y direction that is the first plate width direction.

The second plate face portion **33b3** is formed on the movable-side retained portion **34** side with respect to the switching-bend portion **33b2**. The second plate face portion **33b3** has a flat plate shape with a plate thickness direction facing in the Y direction (a direction orthogonal to the ZX plane).

The second plate face portion **33b3** is parallel to the first plate face portion **33b1**, and can be thought of as being a portion extending toward the other end side (contact portion **35b1, 35b2** side) of the terminal **30**. When thought of in this manner, the second plate face portion **33b3** is a portion having a straight line shaped extension direction. The extension direction of the second plate face portion **33b3** is a direction inclined toward the -Z direction and the X direction inside.

The second coupling portion **33c** is a portion that couples the plate thickness direction switching portion **33b** and the movable-side retained portion **34** together.

The second coupling portion **33c** includes an X direction extension portion **33c1** and a Z direction extension portion **33c2**.

The X direction extension portion **33c1** extends toward the X direction inside from the other end of the second plate face portion **33b3** of the plate thickness direction switching portion **33b**.

A displacement portion **36** is formed to the X direction extension portion **33c1**.

The displacement portion **36** is configured by two bent portions bent in opposite directions to each other at the same angle (preferably an angle less than 90° as illustrated in the drawings). These two bent portions are bent in the plate thickness direction so as to change the plate thickness direction of the second coupling portion **33c** within an XY plane. The plate thickness direction of a portion further to the other end side of the second coupling portion **33c** (the movable-side retained portion **34** side thereof) than the displacement portion **36** thereby faces in the Y direction, and a Y direction position of a portion of the second coupling portion **33c** further to the other end side than the displacement portion **36** is thereby aligned with a Y direction position of the fixed-side retained portion **32**. Namely, a Y direction position of the terminal **30** that is displaced at the plate thickness direction switching portion **33b** is corrected by the displacement portion **36**.

The Z direction extension portion **33c2** extends in the +Z direction from the X direction extension portion **33c1**.

The width dimension (X direction dimension) of the Z direction extension portion **33c2** is smaller than the movable-side retained portion **34** width direction dimension. The Z direction extension portion **33c2** is coupled to a width direction central position of the movable-side retained portion **34**. A portion of the X direction extension portion **33c1** from which the Z direction extension portion **33c2** extends functions as a portion held in place by a tool when the movable-side retained portion **34** is being press-fitted into the movable housing **20**.

The intermediate portion **33** can be divided into portions surrounded by the housings **10, 20**, and a portion not surrounded by the housings **10, 20** (an exposed portion). More specifically, the intermediate portion **33** includes a portion surrounded by the fixed housing **10**, a portion not surrounded by the housings **10, 20**, and a portion surrounded by the movable housing **20**, in that order. The portion surrounded by the fixed housing **10** is part of the first bent portion **33a1** of the first coupling portion **33a**. The portion surrounded by the movable housing **20** is part of the X direction extension portion **33c1** and the Z direction exten-

sion portion **33c2** of the second coupling portion **33c**. The plate thickness direction switching portion **33b** is formed at the portion not surrounded by the housings **10, 20**.

The movable-side retained portion **34** is a portion retained in the movable housing **20**. The movable-side retained portion **34** is retained in the movable housing **20** by being press-fitted into the movable housing **20** with the +Z direction as the press-fit direction. The movable-side retained portion **34** has a plate thickness direction facing in the Y direction, a plate width direction facing in the X direction, and extends in the +Z direction. The movable-side retained portion **34** includes press-fit protrusions **34a**. The press-fit protrusions **34a** are formed only on the X direction inside from out of the plate width directions of the movable-side retained portion **34**. The press-fit protrusions **34a** are formed at plural different locations (two locations in the drawings) in the extension direction of the movable-side retained portion **34**. The press-fit protrusions **34a** formed at the plural locations all bite into the movable housing **20**.

The leading end portion **35** is a portion further toward the other end side than the movable-side retained portion **34**.

The leading end portion **35** includes the contact portions **35b1, 35b2** and resilient support portions **35a1, 35a2**.

The contact portions **35b1, 35b2** are portions that contact the counterpart terminals (omitted in the drawings) of the counterpart connector (omitted in the drawings). The counterpart connector is connected with the -Z direction as the connection direction, and is disposed at the X direction inside with respect to the contact portions **35b1, 35b2**. Namely, the X direction inside direction of the contact portions **35b1, 35b2** makes contact with the counterpart connector.

The contact portions **35b1, 35b2** include a first contact portion **35b1** (first contact portion) and a second contact portion **35b2** (second contact portion).

The first contact portion **35b1** is a contact portion at a position at the near side in the -Z direction, this being the connection direction of the connection target, and the second contact portion **35b2** is a contact portion at a position at the far side in the -Z direction, this being the connection direction of the connection target. The first contact portion **35b1** includes a function to wipe a portion of the connection target that will contact the second contact portion **35b2**.

An indentation **35b3** indented toward the X direction inside is formed at the X direction outside of the first contact portion **35b1**. A cross-sectional area of the first contact portion **35b1** (surface area of cross-section perpendicular to the Z direction) is suppressed from becoming excessively large and impedance is adjusted thereby.

The resilient support portions **35a1, 35a2** are portions that resiliently support the contact portions **35b1, 35b2**.

The resilient support portions **35a1, 35a2** include a first resilient support portion **35a1** and a second resilient support portion **35a2**. The first resilient support portion **35a1** supports the first contact portion **35b1**, and the second resilient support portion **35a2** supports the second contact portion **35b2**. When the counterpart connector (omitted in the drawings) is connected to the connector **100**, the resilient support portions **35a1, 35a2** resiliently deform such that the contact portions **35b1, 35b2** are displaced toward the X direction outside.

The first resilient support portion **35a1** extends from a base thereof substantially parallel to the +Z direction and is connected to the first contact portion **35b1**. The second resilient support portion **35a2** extends from a base thereof in a direction inclined toward the +Z direction and X direction outside, and thereafter extends in a direction inclined toward

11

the +Z direction and the X direction inside and is connected to the second contact portion 35b2. The second resilient support portion 35a2 and the second contact portion 35b2 are disposed at the X direction inside with respect to the first resilient support portion 35a1.

Fixed Housing 10

Next, detailed description follows regarding the fixed housing 10.

As illustrated in FIG. 5, the fixed housing 10 includes a front side terminal retaining portion 11 and a rear side terminal retaining portion 11. The front side terminal retaining portion 11 and the rear side terminal retaining portion 11 have the same structure as each other. These are both referred to simply as terminal retaining portions 11 when not discriminating therebetween.

The terminal retaining portions 11 each include plural array direction walls 12.

The array direction walls 12 are disposed with respect to the fixed-side retained portion 32 of the terminal 30 at positions on both sides thereof in the Y direction, which is the array direction and plate width direction. The fixed-side retained portions 32 are each press-fitted into a space between adjacent array direction walls 12 from out of the plural array direction walls 12. These spaces are open toward the X direction inside. These open portions thereby enable the intermediate portion 33 (more specifically the first bent portion 33a1) of each of the terminals 30 to pass through when the fixed-side retained portion 32 is being press-fitted.

The terminal retaining portions 11 each include an outside wall 13.

The outside wall 13 is disposed at a position on the X direction outside with respect to the fixed-side retained portions 32. The outside wall 13 is connected to the X direction outside ends of the plural array direction walls 12.

The terminal retaining portions 11 each include a top wall 14.

The top wall 14 is positioned further in the +Z direction than the fixed-side retained portion 32 and part of the intermediate portion 33. The top wall 14 is connected to the +Z direction side of the plural array direction walls 12. The top wall 14 extends from a +Z direction end of the outside wall 13 toward the X direction inside.

Movable Housing 20

Next detailed explanation follows regarding the movable housing 20.

As illustrated in FIG. 6, the movable housing 20 includes plural array direction walls 21.

The array direction walls 21 are disposed at positions with respect to parts of the terminals 30 on both sides thereof in the Y direction, which is the array direction. The array direction walls 21 positioned between adjacent terminals 30 from out of the plural array direction walls 21 are sometimes referred to as separation walls 21. The array direction walls 21 include guide faces 21b2 to guide the counterpart connector (omitted in the drawings) to an appropriate position in the X direction.

The array direction walls 21 include a lower array direction wall 21a and an upper array direction wall 21b.

The lower array direction wall 21a corresponds to the movable-side retained portion 34 and part of the intermediate portion 33.

The upper array direction wall 21b corresponds to the leading end portion 35. The upper array direction wall 21b is separated into a front side portion and a rear side portion. A space for inserting part of the counterpart connector (omitted in the drawings) into is formed between the upper

12

array direction wall 21b on the front side and the upper array direction wall 21b on the rear side.

The lower array direction wall 21a is integrally formed with a front side portion and a rear side portion.

5 The movable housing 20 includes a front-rear pair of outside walls 22.

The outside walls 22 are positioned at the X direction outside with respect to part of the terminals 30. The outside walls 22 couple the plural array direction walls 21 together at X direction outside portions thereof. The outside walls 22 each include a guide face 22b1 to guide the counterpart connector (omitted in the drawings) to an appropriate position in the X direction.

15 The outside walls 22 each include a lower outside wall 22a and an upper outside wall 22b.

The lower outside wall 22a corresponds to the movable-side retained portion 34.

20 The upper outside wall 22b corresponds to the leading end portion 35. The upper outside wall 22b is formed further to the X direction outside than the lower outside wall 22a, and a space inside the movable housing 20 is widened at an upper portion thereof.

The movable housing 20 includes an array direction coupling wall 23.

25 The array direction coupling wall 23 couples the plural lower array direction walls 21a together in the array direction.

30 Spaces between the array direction coupling wall 23 and the lower outside wall 22a are spaces through which the leading end portions 35 of the terminals 30 pass when assembling the terminals 30 to the movable housing 20 and in which the movable-side retained portions 34 are disposed. The movable-side retained portions 34 are press-fitted 35 between the array direction coupling wall 23 and the lower outside wall 22a.

35 As illustrated in FIG. 7, enlarged width portions 24 are formed to the array direction walls 21.

The enlarged width portions 24 are portions where the 40 wall thickness of the array direction walls 21 is enlarged.

The enlarged width portions 24 are formed at positions corresponding to the contact portions 35b1, 35b2 of the terminals 30 when in a connected state to the counterpart connector (see FIG. 1, FIG. 1 illustrates the terminals 30 in a state connected to the counterpart connector). A wall face 24a1 of each of the enlarged width portions 24 is disposed in closer proximity to the terminals 30 than a wall face 21b1 of other portions (general portions) of the array direction walls 21. The Y direction dimension of the space in which the contact portions 35b1, 35b2 are disposed thereby becomes smaller, suppressing the contact portions 35b1, 35b2 from being positioned significantly displaced in the Y direction from specific positions thereof. In the following the contact portions 35b1, 35b2 are sometimes referred to as 50 restricted portions 35b1, 35b2. The wall faces 24a1 of the enlarged width portions 24 are sometimes referred to as restricting faces 24a1, and the wall faces 21b1 of the general portions are sometimes referred to as separated faces 21b1. The restricting faces 24a1 and the separated faces 21b1 are 55 both flat faces having a normal direction facing in the Y direction. The restricting faces 24a1 are each formed at a region on the +Z direction and X direction inside of a wall face of the upper array direction wall 21b. This means that the separated face 21b1 is formed at a position displaced from the position of the wall face 24a1 toward the X direction outside, a position displaced from the position of the wall face 24a1 toward the -Z direction, and at a position

60 65

13

displaced from the position of the wall face **24a1** toward the **X** direction outside and the **-Z** direction.

Gap portions **25** are formed in the separation walls **21**.

The gap portions **25** are portions where a gap is formed at a wall thickness direction intermediate portion of the separation walls **21**, and are grooves open toward the **+Z** direction and the **X** direction inside. The gap portions **25** are formed in the array direction walls **21** at positions corresponding to the enlarged width portions **24**. The enlarged width portions **24** are accordingly each configured from a pair of the separation walls **24a** and the gap portion **25** therebetween. The gap portion **25** is accordingly formed between a pair of the wall faces **24a1** provided to the array direction wall **21**, at a position between adjacent of the contact portions **35b1**, **35b2**.

Operation and Advantageous Effects

Next, description follows regarding the operation and advantageous effects of the present exemplary embodiment.

As illustrated in FIG. 1 to FIG. 3, in the present exemplary embodiment the connector **100** includes the plural terminals **30**, and the housings **10**, **20**.

As illustrated in FIG. 7, the housings **10**, **20** include the separation walls **21** positioned between adjacent of the terminals **30**. The separation walls **21** each include one-side opposing faces **21b1**, **24a1**, and other-side opposing faces **21b1**, **24a1**. The one-side opposing faces **21b1**, **24a1** are faces opposing one of adjacent terminals **30**, and the other-side opposing faces **21b1**, **24a1** are faces opposing the other adjacent terminal **30**.

Furthermore, the separation walls **21** are formed between the one-side opposing faces **21b1**, **24a1** and the other-side opposing faces **21b1**, **24a1**, and include the gap portions **25** positioned between the adjacent terminals **30**.

This thereby raises the impedance of close proximity portions of the terminals **30** corresponding to the gap portion **25** in comparison to embodiments not formed with such gap portions **25**. As a result thereof, the impedance of the terminals **30** can be suppressed from falling excessively.

Moreover, in the present exemplary embodiment the terminals **30** include the restricted portions **35b1**, **35b2**. The one-side opposing faces **21b1**, **24a1** include the one-side restricting face **24a1** that restricts movement of one of adjacent restricted portions **35b1**, **35b2** in a direction approaching the other thereof, and the other-side opposing faces **21b1**, **24a1** include the other-side restricting face **24a1** that restricts movement of the other adjacent restricted portion **35b1**, **35b2** in a direction approaching the one thereof.

Part of the terminals **30** (the restricted portions **35b1**, **35b2**) are thereby suppressed from being disposed at positions displaced from specific positions.

Moreover, the restricted portions **35b1**, **35b2** are the contact portions **35b1**, **35b2** configured to contact the connection target (counterpart connector).

This means that the contact portions **35b1**, **35b2** are suppressed from being disposed at positions displaced from the specific positions.

Note that the restricted portions **35b1**, **35b2** are disposed in the vicinity of the separation walls **21**, and so are liable to suffer an excessive drop in impedance. The gap portions **25** are accordingly preferably respectively positioned between the adjacent restricted portions **35b1**, **35b2** (the contact portions **35b1**, **35b2**) as in the present exemplary embodiment.

14

Moreover, in the present exemplary embodiment, the contact portions **35b1**, **35b2** include the first contact portion **35b1** and the second contact portion **35b2**, which is positioned further toward the far side than the first contact portion **35b1** in the connection direction of the connection target (counterpart connector).

The gap portions **25** are accordingly positioned between the adjacent first contact portions **35b1** and are also positioned between the adjacent second contact portions **35b2**.

10 This thereby enables the first contact portion **35b1** and the second contact portion **35b2** to be suppressed from being disposed at positions displaced from the specific positions while also enabling an excessive drop in impedance of the first contact portion **35b1** and the second contact portion **35b2** to be suppressed.

Moreover, in the present exemplary embodiment, a portion of the gap portion **25** positioned between the adjacent first contact portions **35b1** and a portion thereof positioned between the adjacent second contact portions **35b2** are 20 coupled together in the connection direction (**Z** direction).

This accordingly enables the gap portion **25** to be more easily formed than embodiments in which a portion of the gap portion **25** positioned between the adjacent first contact portions **35b1** and a portion thereof positioned between the adjacent second contact portions **35b2** are not coupled together.

Moreover, in the present exemplary embodiment, each of the plural terminals **30** includes the resilient support portions **35a1**, **35a2** that resiliently support the contact portions **35b1**, **35b2**.

25 The separation walls **21** are configured so as to be interposed between the adjacent resilient support portions **35a1**, **35a2**.

Shorting between adjacent resilient support portions **35a1**, **35a2** caused by metal-plating gas is thereby prevented at the portions where the separation walls **21** are interposed between the adjacent resilient support portions **35a1**, **35a2**.

Moreover, in the present exemplary embodiment, the separation walls **21** each include either the one-side separated face **21b1**, or the other-side separated face **21b1**, or both thereof (both in the present exemplary embodiment).

40 The one-side separated face **21b1** is a face facing toward the side of one of the adjacent resilient support portions **35a1**, **35a2**, and is a face formed at a position further away from the one resilient support portions **35a1**, **35a2** than the one restricting face **24a1** in an adjacency direction (the direction of adjacency between the adjacent resilient support portions **35a1**, **35a2**, the **Y** direction). The other-side separated face **21b1** is a face facing toward the side of the other adjacent resilient support portions **35a1**, **35a2**, and is a face formed at a position further away from the other of the resilient support portions **35a1**, **35a2** than the other restricting face **24a1** in the adjacency direction (**Y** direction).

45 The impedance of the resilient support portions **35a1**, **35a2** can accordingly be suppressed from dropping excessively in comparison to embodiments in which the separation walls **21** lack both the one-side separated face **21b1** and the other-side separated face **21b1** (e.g. a second modified example described later).

60 Moreover, in the present exemplary embodiment the one-side separated face **21b1** or the other-side separated face **21b1** provided to the separation wall **21** includes a near-side separated face **21b1**. The near-side separated face **21b1** is a face formed at a position respectively displaced from a position of the one-side restricting face **24a1** or a position of the other-side restricting face **24a1** in the opposite direction (hereafter referred to as “opposite-to-contact direction”,

15

which is the X direction outside) to a contact direction (a direction in which the contact portions **35b1**, **35b2** contact the connection target (counterpart connector)).

Thus when part of the resilient support portions **35a1**, **35a2** (upper portions of the first resilient support portion **35a1** in the present exemplary embodiment) is disposed at a position displaced from the position of the contact portions **35b1**, **35b2** in the opposite-to-contact direction, the impedance of this part of the resilient support portions **35a1**, **35a2** can be suppressed from dropping excessively.

Moreover, in the present exemplary embodiment, the one-side separated face **21b1** or the other-side separated face **21b1** respectively provided to each of the separation walls **21** includes a first far-side separated face **21b1**. The first far-side separated face **21b1** is a face formed at a position displaced from the position of the one restricting face **24a1** or the other restricting face **24a1** toward the far side in the connection direction of the connection target (counterpart connector).

Thus when part of the resilient support portions **35a1**, **35a2** (the second resilient support portion **35a2** in the present exemplary embodiment) is disposed at a position displaced from the position of the contact portions **35b1**, **35b2** toward the far side in the connection direction, the impedance of this part of the resilient support portions **35a1**, **35a2** can be suppressed from dropping excessively.

Moreover, in the present exemplary embodiment the one-side separated face **21b1** or the other-side separated face **21b1** includes a second far-side separated face **21b1**. The second far-side separated face **21b1** is a face formed at a position respectively displaced from the position of the one restricting face **24a1** or the other restricting face **24a1** toward the far side in the opposite-to-contact direction and the connection direction.

Thus when part of the resilient support portions **35a1**, **35a2** (a lower portion of the first resilient support portion **35a1** in the present exemplary embodiment) is disposed at the position displaced from the position of the contact portions **35b1**, **35b2** toward the far side in the opposite-to-contact direction and the connection direction, the impedance of this part of the resilient support portions **35a1**, **35a2** can be suppressed from dropping excessively.

Modified Examples

FIG. 8 to FIG. 11 are diagrams illustrating connectors of a first modified example to a fourth modified example. Points of difference between the above exemplary embodiment and each of the modified examples are merely in a structure of the movable housing.

FIG. 8 illustrates the first modified example.

In a movable housing **20A** of the first modified example an upper array direction wall **21b** is not coupled to an upper outside wall **22b**. This means that there is a space between the upper array direction wall **21b** and the upper outside wall **22b**, and this space extends in the Y direction. Namely, there are no portions that correspond to the near-side separated face **21b1** and the second far-side separated face **21b1** of the upper array direction wall **21b** of the above exemplary embodiment. Note that there is a portion present that corresponds to the first far-side separated face **21b1**.

Thus when part of the resilient support portions **35a1**, **35a2** is disposed at a position displaced from the position of the contact portions **35b1**, **35b2** in the opposite-to-contact direction (X direction outside), the impedance of this part of the resilient support portions **35a1**, **35a2** can be suppressed from dropping excessively even more. Moreover, when part

16

of the resilient support portions **35a1**, **35a2** is disposed at a position displaced from the position of the contact portions **35b1**, **35b2** in the opposite-to-contact direction (X direction outside) and in the connection direction far side (-Z direction), the impedance of this part of the resilient support portions **35a1**, **35a2** can be suppressed from dropping excessively even more. Note that this advantageous effect is an effect exhibited even without the gap portions **25** being formed to the separation walls **21**.

FIG. 9 illustrates the second modified example.

In a movable housing **20B** of the second modified example enlarged width portions (see the enlarged width portions **24** of FIG. 7) are not formed to the array direction walls **21**. However, a wall face **21b1** of the array direction wall **21** is in close proximity to the terminal **30**, and so this can be thought of as the entire array direction wall **21** configuring an enlarged width portion.

In the present modified example the wall face **21b1** of the array direction wall **21** corresponds to a "restricting face" and a "opposing face".

FIG. 10 illustrates the third modified example.

In a movable housing **20C** of the third modified example there are plural (two) gap portions **25** formed to each of the separation walls **21**. The impedance of the restricted portions **35b1**, **35b2** can also be suppressed from dropping excessively in cases in which there are plural of the gap portions **25** formed in this manner.

FIG. 11 illustrates the fourth modified example.

In a movable housing **20D** of the fourth modified example a depth of each of the gap portions **25** (depth toward the X direction outside) is deeper than in the above exemplary embodiment. More specifically, the depth of the gap portion **25** is the same as a depth of a space formed between adjacent of the separation walls **21** in which the terminals **30** are disposed.

In the present modified example, due to the presence of the gap portions **25**, not only can the impedance of the contact portions **35b1**, **35b2** be suppressed from dropping excessively, but the impedance of the resilient support portions **35a1**, **35a2** can also be suppressed from dropping excessively.

Although the present disclosure has been described by way of exemplary embodiments and modified examples, the present disclosure is not limited thereto.

EXPLANATION OF REFERENCE NUMERALS

- 100 connector
- 10, 20 housings
- 10 fixed housing
- 20 movable housing
- 20A movable housing
- 20B movable housing
- 20C movable housing
- 20D movable housing
- 21 array direction wall (separation wall)
- 21a lower array direction wall
- 21b upper array direction wall
- 21b1 separated face (one-side separated face, other-side separated face, near-side separated face, first far-side separated face, second far-side separated face) (one-side opposing face, other-side opposing face)
- 22 outside wall
- 22a lower outside wall
- 22b upper outside wall
- 24 enlarged width portion

17

- 24a1** restricting face (one-side restricting face, other-side restricting face) (one-side opposing face, other-side opposing face)
- 25** gap portion
- 30** terminal
- 35a1, 35a2** resilient support portion
- 35a1** first resilient support portion
- 35a2** second resilient support portion
- 35b1, 35b2** contact portion (restricted portion)
- 35b1** first contact portion (restricted portion)
- 35b2** second contact portion (restricted portion)
- The invention claimed is:
1. A connector comprising a plurality of terminals and a housing, wherein:

the housing includes a separation wall positioned between adjacent of the terminals; 15

the separation wall includes

    - a one-side opposing face that opposes one of the adjacent terminals,
    - an other-side opposing face that opposes the other of the adjacent terminals, and
    - a gap portion formed between the one-side opposing face and the other-side opposing face;

wherein air or a member having a lower permittivity than the housing is disposed in the gap portion, and no 25 member having a higher permittivity than the housing is disposed in the gap portion.
  2. The connector of claim 1, wherein:

the terminals each include a restricted portion;

the one-side opposing face includes a one-side restricting face that restricts one of adjacent of the restricted portions from moving in a direction approaching the other thereof;

the other-side opposing face includes an other-side restricting face that restricts the other adjacent restricted portion from moving in a direction approaching the one thereof; and

the restricted portion includes a contact portion configured to contact a connection target. 35
  3. The connector of claim 2, wherein:

the contact portion includes

    - a first contact portion, and
    - a second contact portion positioned further to a far side than the first contact portion in a connection direction of the connection target; and

the gap portion is positioned between adjacent of the first contact portions and is positioned between adjacent of the second contact portions. 45
  4. The connector of claim 3, wherein a portion of the gap portion positioned between the adjacent first contact portions and a portion of the gap portion positioned between the adjacent second contact portions are coupled together in the connection direction. 50
  5. The connector of claim 2, wherein:

each of the plurality of terminals includes a resilient support portion that resiliently supports the contact portion; and

the separation wall is configured so as to be interposed between adjacent of the resilient support portions.
  6. The connector of claim 5, wherein:

the separation wall includes either

    - a one-side separated face that is a face facing a side of one of the adjacent resilient support portions and that is formed at a position separated from the one adjacent resilient support portion further than the one-side restricting face in an adjacency direction of the adjacent resilient support portions, or

18

- an other-side separated face that is a face facing toward a side of the other adjacent resilient support portion and that is formed at a position separated from the other adjacent resilient support portion further than the other-side restricting face in the adjacency direction of the adjacent resilient support portions, or both thereof.
7. The connector of claim 6, wherein:

the one-side separated face or the other-side separated face provided to the separation wall includes a near-side separated face formed at a position displaced from a position of the one-side restricting face or the other-side restricting face in an opposite direction to a contact direction in which the contact portion contacts the connection target.
  8. The connector of claim 6, wherein:

the one-side separated face or the other-side separated face provided to the separation wall includes a first far-side separated face formed at a position displaced from a position of the one-side restricting face or the other-side restricting face toward a far side in a connection direction of the connection target.
  9. The connector of claim 6, wherein:

the one-side separated face or the other-side separated face provided to the separation wall includes a second far-side separated face formed at a position that is displaced from a position of the one-side restricting face or the other-side restricting face in an opposite direction to a contact direction in which the contact portion contacts the connection target and toward a far side in the connection direction of the connection target.
  10. The connector of claim 2, wherein:

the contact portion includes

    - a first contact portion, and
    - a second contact portion positioned further to a far side than the first contact portion in a connection direction of the connection target;

each of the plurality of terminals includes a resilient support portion that resiliently supports the contact portion;

the separation wall is configured so as to be interposed between adjacent of the resilient support portions;

the separation wall includes either

    - a one-side separated face that is a face facing a side of one of adjacent of the resilient support portions and that is formed at a position separated from the one adjacent resilient support portion further than the one-side restricting face in an adjacency direction of the adjacent resilient support portions, or
    - an other-side separated face that is a face facing toward a side of the other adjacent resilient support portion and that is formed at a position separated from the other adjacent resilient support portion further than the other-side restricting face in the adjacency direction of the adjacent resilient support portions, or both thereof; and

the one-side separated face or the other-side separated face provided to the separation wall includes

    - a near-side separated face formed at a position displaced from a position of the one-side restricting face or the other-side restricting face in an opposite direction to a contact direction in which the contact portion contacts the connection target,
    - a first far-side separated face formed at a position displaced from a position of the one-side restricting

face or the other-side restricting face toward a far side in a connection direction of the connection target, and

a second far-side separated face formed at a position that is displaced from a position of the one-side restricting face or the other-side restricting face in an opposite direction to the contact direction in which the contact portion contacts the connection target and toward a far side in the connection direction of the connection target. 10

11. The connector of claim 1, wherein:

the terminals each include a first contact element and a second contact element;
the first contact element includes a first contact portion and a first resilient support portion that resiliently 15 supports the first contact portion; and
the second contact element includes a second contact portion positioned further to a far side than the first contact portion in a connection direction of a connection target and a second resilient support portion that 20 resiliently supports the second contact portion.
